PAPER TOWELING

Marilyn J. Cross, Bay, Wis., assignor to Fort Howard
Paper Company, Green Bay, Wis.

Filed Mar. 18, 1971, Ser. No. 125,910

Term of patent 14 years

Int. Cl. D5—03

U.S. Cl. D59—2

The figure is a top plan view of paper toweling showing my new design, the dimpling shown broken away for convenience of illustration being continuous throughout.

The drawing has been lined for color.

I claim:

The ornamental design for a paper toweling, as shown and described.
